TANK TRUCK

Melvin W. Krueger, Madison, Wis., assignor to Dairy Equipment Company, Madison, Wis., a corporation of Wisconsin

Filed Sept. 15, 1961, Ser. No. 66,726

Term of patent 14 years

(Cl. D14—3)

FIG. 1 is a perspective view of a tank truck showing my new design;

FIG. 2 is a top plan view of the tank thereof;

FIG. 3 is a side elevational view thereof; and

FIG. 4 is a rear elevational view thereof.

The dominant features of my design reside in the portions shown in full lines. The side not shown is a mirror image of the side shown and the front is substantially plain. The portions shown in broken lines have been omitted from FIGS. 2, 3, and 4 for convenience of illustration.

I claim:

The ornamental design for a tank truck, substantially as shown and described.
